CLAIM

The ornamental design for a wand for a roller blind as shown and described.

DESCRIPTION

FIG. 1 is an isometric top front right view of a wand for a roller blind of the present invention;

FIG. 2 is an isometric top back left view thereof; and

FIG. 3 is a front view thereof.

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines depict portions of the wand for a roller blind that form no part of the claimed design.
